VACUUM-OPERATED GEAR SHIFTER

Application filed January 20, 1928. Serial No. 248,214.

This invention relates to an improvement in vacuum-operated gear-shifters primarily designed for shifting the transmission-gears of automobiles, though not so limited.

The object of this invention is to produce a simple and reliable vacuum-operated gear-shifter constructed with particular reference to improved means for automatically admitting atmospheric-air into the vacuum-compartments thereof when suction is applied to a complementary compartment.

With this object in view, my invention consists in a vacuum-operated gear-shifter characterized by its provision with two complementary suction-compartments adapted to be alternately connected to a source of vacuum; a gear-shifter member actuated in reverse directions by the application of suction to the said compartments respectively; two atmospheric-air inlet-ports respectively opening into the said compartments; two suction-operated valves normally closing the said ports respectively; a valve-chamber for each of the said valves; and a duct extending from each of the said compartments to the valve-chamber of the valve controlling the port in the opposite compartment; whereby, when the source of suction is connected to one compartment to move the said gear-shifting member, the inlet-port in the opposite complementary compartment will be automatically opened to permit the ingress of atmospheric-air thereinto.

My invention further consists in a vacuum-operated gear-shifter characterized as above and having certain other details of construction and combinations of parts as will be hereinafter described and particularly recited in the claims.

In the accompanying drawings:

Fig. 1 is a top or plan view of a vacuum-operated gear-shifter constructed in accordance with my invention, the selector-valve mechanism being shown in horizontal section;

Fig. 2 is a view thereof in end elevation, with a portion of the casing broken away and the selector-valve in vertical section;

Fig. 3 is a longitudinal sectional view on the line 3-3 of Fig. 1; and

Fig. 4 is a schematic sectional view of my improved vacuum-operated gear-shifter showing, in particular, the ducts connecting each suction-compartment with the valve-chamber of the valve controlling the entry of atmospheric-air into its complementary compartment.

In carrying out my invention as herein shown, I employ a cylinder-block 10 bored out to form two parallel cylinders 11 and 12, both of which are closed at one end by walls 13 formed integral with the said cylinder-block and at their opposite ends closed by a removable cylinder-head 14.

The cylinder 11 receives within it a piston 15 which virtually divides it into two suction-compartments 16 and 17 which, for convenience of description, I shall designate, respectively, as the "first-speed suction-compartment" and the "reverse-speed suction-compartment." The said piston consists of a flexible washer-like packing-member 18 clamped between a piston-plate 19 and a clamping-plate 20 by means of screws 21, and provided with two oppositely-extending flexible annular flanges 22-22 engaging the cylinder-wall. Extending axially through the said piston and fastened to the piston-plate 19 thereof by means of a pin 23 is a piston-rod 24 which slides at one end in a bearing 25 formed in the integral wall 13 of the cylinder-block 10 and at its opposite end in a bearing 26 formed in the removable cylinder-head 14. To prevent atmospheric-air from entering the cylinder 11 between the surfaces of the bearings 25 and 26 aforesaid and the respective ends of the piston-rod 24, I employ two packing-washers 27 and 28 respectively secured to the wall 13 and cylinder-head 14 by plates 29 and screws 30.

Similarly, the cylinder 12 receives within it a piston 31 which virtually divides it into two suction-compartments 32 and 33, respectively constituting the third- and second-speed suction-compartments of my improved vacuum-operated gear-shifter. The said piston 31 corresponds in details of construction to the piston 15 before described and, like the latter, is mounted upon a piston-rod 34 sliding in bearings and having packing-washers, 100

etc., corresponding to those of the piston-rod 24 and designated by corresponding reference numerals.

The piston-rods 24 and 34 have respectively secured to them downwardly-projecting centrally-offset gear-shifting arms 35 and 36, the lower ends of which are adapted to extend into the transmission-case (not shown) of an automobile for the purpose of moving the various gears therein into and out of mesh in the same manner as the same are ordinarily operated by means of the customary manual shift-lever.

The suction-compartments 16, 17, 32, and 33 have respectively connected to them suction-ducts 37, 38, 39, and 40 which lead through to the outer face of a valve-seat member 41 secured to one side of the cylinder-block 10. Midway the length of the cylinders 11 and 12 suction-ducts 42 and 43 lead therefrom respectively to the outer face of the valve-seat member 41 aforesaid.

For the purpose of connecting a main suction-pipe 44 leading to the valve-seat member 41 from the intake-manifold of an automobile, or other suitable source of suction, to any one or more of the ducts 37, 38, 40, 42, and 43 to appropriately actuate the pistons and thus effect the shifting of gears, I employ a reciprocating selector-valve slide 45 provided, in its inner face, with irregularly-shaped channels 46, and pressed snugly against the outer face of the valve-seat member 41 by means of a spring 47 acting through a click-ball 48 and spaced-notches 49 in the said valve-slide 45.

The particular nature and arrangement of the selector-valve and ducts above described form, in themselves, no part of my present invention and require no detailed description other than to say that the reciprocating selector-valve slide 45 is adapted to connect the main suction-pipe 44 to the respective ducts of the suction-compartments 16-17, 32-33 of the cylinders 11 and 12 in the manner hereinafter described.

For the purpose of admitting atmospheric-air into the suction-compartments 16-17, 32-33 under certain conditions as will hereinafter appear, each of the same has leading into it from the atmosphere an atmospheric-air inlet-port 50 normally closed by a tapered piston-valve 51 having its outer end shaped to form a hollow cylinder 52 reciprocating within a piston-chamber 53, the inner end of which intersects the said port 50 and is formed with a beveled valve-seat 54 engaged by the tapered inner face of the valve 51 aforesaid. A helical spring 54^a normally maintains the valve 51 in engagement with the seat 54 to prevent the ingress of atmospheric-air through the port 50.

Thus, as shown and described, each of the suction-compartments 16-17, 32-33, has leading into it an atmospheric-air inlet-port

50 normally closed by a valve 51, which latter is adapted, as will now appear, to be automatically drawn off its seat 54 when a partial vacuum is created in a complementary suction-compartment. For this latter purpose, the outer end of the piston-chamber 53 of the valve 51 controlling the port 50 leading into the suction-compartment 16 is connected by a duct 55 leading to the complementary suction-compartment 17. Similarly, the outer end of the piston-chamber 53 of the valve 51 controlling the port 50 leading into the suction-compartment 17 is connected by a duct 56 to the suction-compartment 16. In a like manner, the outer end of the piston-chamber 53 of the valve 51 controlling the port 50 leading into the suction-compartment 32 in the cylinder 12 is connected by a duct 57 to the complementary suction-compartment 33 in the said cylinder. Conversely, the outer end of the piston-chamber 53 of the valve 51 controlling the port 50 leading into the suction-compartment 33 is connected by a duct 58 to the suction-compartment 32 aforesaid.

When it is desired to shift the gears of an automobile into what is commonly known as "first-speed," the reciprocating selector-valve slide 45 will be moved by means of a flexible wire 59 secured to it by a set-screw 60, so as to cause its irregular channels 46 to connect the duct 37 leading to the low-speed suction-chamber 16, and the neutral duct 43 leading to the center of the cylinder 12, with the main suction-pipe 44. With the suction-connection made as just described, the piston 31 will be drawn by suction to its central position within the cylinder 12, as shown in Fig. 4 (if it is not already at this point), to shift the second and third-speed gears which it operates into their neutral position. Concurrently, a partial vacuum will be created in the low-speed suction-compartment 16 with the effect of moving the piston 15 from right to left and through its piston-rod 24 and gear-shifting arm 34 correspondingly move the first-speed gear into operative position.

It is obvious that the partial vacuum created within the suction-compartment 16 cannot act permissively to move the piston 15, together with its rod 24, from right to left as above described unless atmospheric-air is admitted into the opposite complementary suction-compartment 17. The admittance of the required atmospheric-air, as above indicated, into the suction-compartment 17 is automatically effected by the suction in the compartment 16 which, through the duct 56, acts to create a partial vacuum in the piston-chamber 53 of the valve 51 controlling the atmospheric-air inlet-port 50 of the said compartment 17 with the effect of moving the said valve outward clear of its seat 54 against the yielding resistance of the spring 54^a and thus opening the atmospheric-air inlet-port 50 in question.

For the purpose of insuring the return to its neutral position of either of the pistons 15 and 31 before the other can be moved from its neutral position, I employ a so-called 5 "drift-lock" mechanism of ordinary form and consisting, as herein shown, of a rod 61 reciprocating transversely in a suitable guide in the cylinder-head 14 and extending between the piston-rods 24 and 34, which latter 10 are each provided with a notch 62 adapted to receive the rounded adjacent ends 63 of the said bar. By reference to Fig. 4 of the drawings, it will be seen that suction cannot act to move the piston-rod 34 in either direction until the piston-rod 24 has been moved to its central position, at which time its notch 62 will be brought into registration with the drift-lock rod 61, permitting the same to move into the said notch concurrently with 15 the withdrawal of its opposite end from the corresponding notch in the piston-rod 34. It will thus appear that neither one of the piston-rods can be moved from its neutral position until the other complementary piston-rod is in its neutral position.

When a partial vacuum is created within the suction-compartment 17 by suitably moving the selector-valve slide 45 so as to connect its duct 38 with the main suction-pipe 44, the 20 valve 51 controlling the atmospheric-air inlet-port 50 into the complementary suction-compartment 16 will be drawn off its seat by the suction transmitted through the duct 55 and atmospheric-air permitted to enter the 25 said compartment 16 for moving the piston 15 and piston-rod 24 from left to right into the position shown by Fig. 4 of the drawings.

In a like manner, when suction is created within either of the compartments 32 or 33 30 of the cylinder 12, the valve normally closing the atmospheric-air inlet-port of the other of the two compartments will be drawn off its seat and atmospheric-air permitted to enter to move the piston 31 and piston-rod 34.

45 I claim:

1. A vacuum-operated gear-shifter, comprising two vacuum-compartments adapted to be alternately connected to a source of vacuum; a gear-shifting member actuated in 50 reverse directions by the application of suction to the said compartments respectively; two atmospheric-air inlet-ports respectively opening into the said compartments; two independently-movable suction-operated valves 55 normally closing the said ports respectively and constructed and arranged to be moved into their port-opening positions by suction; a valve-chamber for each of said valves; and a duct extending from each of the said compartments to the valve-chamber of the valve 60 controlling the port in the opposite compartment; whereby, when a source of suction is connected to one compartment to move the said gear-shifting member, the inlet-port in the opposite compartment will be automatically opened to permit the ingress of atmospheric-air thereinto without admitting such air into the compartment under suction.

cally opened to permit the ingress of atmospheric-air thereinto without admitting such air into the compartment under suction.

2. A vacuum-operated gear-shifter, comprising two vacuum-compartments adapted to be alternately connected to a source of vacuum; a gear-shifting member actuated in reverse directions by the application of suction to the said compartments respectively; two atmospheric-air inlet-ports respectively opening into the said compartments; two independently movable reciprocating suction-operated piston-valves normally closing the said ports respectively and constructed and arranged to be moved into their port-opening positions by suction; a valve-cylinder for each of the said valves; and a duct extending from each of the said compartments to the valve-cylinder of the valve controlling the port in the opposite compartment; whereby, when a source of suction is connected to one compartment to move the said gear-shifting member, the inlet-port in the opposite compartment will be automatically opened to permit the ingress of atmospheric air thereinto without admitting such air into the compartment under suction.

3. A vacuum-operated gear-shifter, comprising two vacuum-compartments adapted to be alternately connected to a source of vacuum; a gear-shifting member actuated in reverse directions by the application of suction to the said compartments respectively; two atmospheric-air inlet-ports respectively opening into the said compartments; two independently-movable suction-operated valves normally closing the said ports respectively and constructed and arranged to be moved into their port-opening positions by suction; spring-means arranged to yieldingly urge the said valves into their port-closing positions; a valve-chamber for each of the said valves; and a duct extending from each of the said compartments to the valve-chamber of the valve controlling the port in the opposite compartment; whereby, when a source of suction is connected to one compartment to move the said gear-shifting member, the inlet-port in the opposite compartment will be automatically opened to permit the ingress of atmospheric-air thereinto without admitting such air into the compartment under suction.

4. A vacuum-operated gear-shifter, comprising a cylinder; a piston therein virtually dividing the same into two compartments; two atmospheric-air inlet-ports respectively opening into the said compartments; two independently-movable suction-operated valves normally closing the said ports respectively and constructed and arranged to be moved into their port-opening positions by suction; a valve-chamber for each of the said valves; and a duct extending from each of the said compartments to the valve-chamber of the valve controlling the port in the opposite compartment; whereby, when a source of suction is connected to one compartment to move the said gear-shifting member, the inlet-port in the opposite compartment will be automatically opened to permit the ingress of atmospheric-air thereinto without admitting such air into the compartment under suction.

valve controlling the port in the opposite compartment; whereby, when a source of suction is connected to one compartment to move the said piston, the inlet-port in the opposite compartment will be automatically opened to permit the ingress of atmospheric-air thereinto without admitting such air into the compartment under suction.

5. A vacuum-operated gear-shifter, comprising a cylinder; a piston therein virtually dividing the same into two compartments; two atmospheric-air inlet-ports respectively opening into the outer ends of the said compartments; two independently-movable reciprocating suction-operated piston-valves normally closing the said ports respectively and constructed and arranged to be moved into their port-opening positions by suction; spring means arranged to yieldingly urge the 10 said valves into their port-closing positions; a valve-cylinder for each of the said valves arranged substantially parallel with the axis of the first-mentioned cylinder; and a duct extending from each of the said compartments to the valve-cylinder of the valve controlling the port in the opposite compartment; whereby, when a source of suction is connected to one compartment to move the 15 said piston, the inlet-port in the opposite compartment will be automatically opened to permit the ingress of atmospheric-air thereinto without admitting such air into the compartment under suction.

In testimony whereof, I have signed this
35 specification.

DOUGLAS F. LINSLEY.
